HOWARD V. BRUMLEY, OF PLANDOME, NEW YORK, ASSIGNOR TO WHITALL TATUM COMPANY, OF NEW YORK, N. Y., A CORPORATION OF NEW JERSEY.

NURSING-NIPPLE.

1,168,056.

Specification of Letters Patent. Patented Jan. 11, 1916.

Application filed October 15, 1915. Serial No. 55,995.

To all whom it may concern:

Be it known that I, HOWARD V. BRUMLEY, a citizen of the United States, residing at Plandome, in the county of Nassau and State of New York, have invented new and useful Improvements in Nursing-Nipples, of which the following is a specification.

This invention relates essentially to that kind of elastic nursing nipples which is adapted for attachment to the neck of a baby's milk bottle.

The object of the invention is to provide the nipple with a stem or top portion so shaped that the wall of the nipple is prevented from collapsing. The invention is designed to obviate the adhesion of the walls, and consequent break down of the nipple, caused by the compression of the stem while the liquid is being sucked through.

The invention comprehends a nipple which is inexpensive, non-collapsible, can be readily cleaned, and has no sharp corners for the lodgment of particles of milk or other injurious unsanitary matter. By reason of the peculiar tapered triangular formation of the stem the nipple can be conveniently turned inside out in order to facilitate cleaning and removal of any foreign matter lodged on the inner surface of the nipple.

The novel features of the invention are more fully described in the following specification and claims and illustrated in the accompanying drawing in which:

Figure 1 represents a side elevation of a nipple embodying this invention. Fig. 2 is a vertical central section of the same. Fig. 3 is a plan view of the same on a larger scale. Fig. 4 is a horizontal section taken along the line $y-y$ of Fig. 1 on a larger scale.

In this drawing the letter a designates a cylindrical tubular base adapted for insertion over the neck of any ordinary nursing bottle. The lower end of the base is provided with a flange b the inner portion of which is of somewhat smaller diameter than the inner surface of the tubular base member in order to give tight closure when the nipple is fitted to the neck of a bottle.

The upper portion of the tubular base has a shoulder c from which projects a tubular stem d having a hemispherical top e form-

ing the apex of the nipple. At the top of the hemispherical member is located a hole f for the liquid to pass through. The stem d as shown is angular with three flat sides extending from the shoulder to the top. The sides are inclined with the smaller diameter at the vertices where the hemispherical top is joined to the sides, and the largest diameter at the shoulder c located on the base. The convergent angles of the triangular walls are joined together by curved segmental walls g projecting from the shoulder to the top of the nipple, thus avoiding any angles and eliminating any crevices for the lodgment of dirt.

It will be seen that the tubular elastic stem forms a triangular pyramidal cone, with a domed apex, so that when the article is in use and the walls are compressed creating a suction in the nipple the walls will form diverging angles at their inner surfaces and sticking together of the walls will be practically avoided.

I claim:

1. A nursing nipple comprising a base adapted for insertion on the neck of a bottle, and an angular tubular stem projecting from the base.

2. A nursing nipple comprising a base adapted for insertion on the neck of a bottle, and a tapered angular tubular stem projecting from the base.

3. A nursing nipple comprising a cylindrical flanged base adapted for insertion on the neck of a bottle, and a tapered angular tubular stem projecting from the base.

4. A nursing nipple comprising a cylindrical shouldered and flanged base adapted for insertion on the neck of a bottle, and a tapered angular stem having a hemispherical apex.

5. A nursing nipple comprising a cylindrical shouldered and flanged base adapted for insertion on the neck of a bottle, and a triangular tapered stem projecting from the base, said stem having a hemispherical apex.

6. A nursing nipple comprising a cylindrical flanged and shouldered base adapted to fit on the neck of a bottle, a triangular conical stem projecting from the base, curved walls joining the convergent angles, said stem having a hemispherical apex.

7. A nursing nipple comprising a cylin-

drical tubular base having a flanged lower portion and a shouldered top to fit on the neck of a bottle, a triangular tapered stem projecting from the shoulder, the angles of 5 the triangle being joined together by segmental walls, and a hemispherical member surmounting the stem.

In testimony whereof I have hereunto set my hand in the presence of two subscribing witnesses.

HOWARD V. BRUMLEY.
